EARLE E. TANNAR, OF AKRON, OHIO.

TIRE-CORE.

1,157,263.

Specification of Letters Patent.

Patented Oct. 19, 1915.

Application filed March 12, 1914. Serial No. 824,127.

To all whom it may concern:

Be it known that I, EARLE E. TANNAR, a citizen of the United States, residing at Akron, in the county of Summit and State of Ohio, have invented a certain new and useful Improvement in Tire-Cores, of which the following is a full, clear, and exact description, reference being had to the accompanying drawings.

This invention relates to molds for vehicle tires and more particularly to the "core" portions of such molds.

As is well known to those skilled in this art, the cores of molds of this type are made up of a plurality of segments and the end faces of one of the segments are defined by planes which extend parallel to each other, whereby the core may be conveniently collapsed merely by moving this segment inwardly within the annular space defined by the assembled core segments.

As is also well known, it is customary to assemble the core segments by means of a "gathering ring" fitted into segmental annular recesses in the inner shoulders of the segments, said recesses, when the segments are assembled, forming a complete annulus extending around one of the lateral faces of the inner shouldered portion of the core. It is the general purpose of this invention to provide means whereby the core segments may be more conveniently and effectively assembled and disassembled, and whereby the life and effectiveness of the gathering ring may be increased and extended.

In the drawings forming part hereof, Figure 1 represents a side elevation of a core of the character referred to having my new gathering ring applied thereto; Fig. 2 is a sectional view, corresponding to the line 2—2 of Fig. 1, showing the parts of the gathering ring in the position which they assume when the ring is driven home; and Fig. 3 is a similar view showing the positions of the parts of the ring immediately after the insertion of the ring into its groove or recess.

Describing the parts by reference characters, 1, 2, 3 and 4 denote the segments of a core, which core, with the exception to be noted hereinafter, is of ordinary or standard construction. The segment 4 is provided with the parallel faces 5 which enable it to be moved inwardly, when the gathering ring is removed, to facilitate the collapse of the core. Each segment is provided in its inner

shouldered portion with a recess 6. This recess projects inwardly from one face of the shoulder and is arcuate in shape, the recesses of the segments uniting, when the segments are assembled, to form a complete annular recess for the core. The outer face 7 of the recess is straight or cylindrical; that is to say, it projects at right-angles to the face 9 of the inner shoulder of the core section. The inner face 8 (that is, the face which is toward the center of the core) is bevel, whereby the recess is wedge-shaped in section. The gathering ring which I employ with this construction is a ring which is also wedge-shaped in section, but which consists of two parts, namely: an outer cylindrical ring section and an inner ring section. The outer ring section 10 has a vertical or straight cylindrical face 11 coöperating with the corresponding outer face 7 of the recess, while the inner face 12 of the outer ring section is substantially parallel to the face 11, but is provided with a recess or groove 13 extending entirely around the inner face of the ring. Coöperating with the inner face of the outer ring section is the inner ring section 14. This inner ring section is itself a split ring having a straight or vertical cylindrical face 15 adapted to fit against the corresponding face 12 of the outer ring section and provided with a tongue 16 adapted to enter the groove or recess 13, but of considerably less width than said groove or recess. The inner face 17 of the inner ring section 14 is beveled to correspond to the bevel surface 8 of the recess 6.

With this construction, it will be evident that the inner ring section 14 may be applied to the outer ring section by bringing the ends 14^a together. In assembling the core sections, the inner ring section will naturally drop by gravity to the position shown in Fig. 3, namely: with its lower end projecting below the lower end of the outer section. When the four core segments are moved up into substantial registration, the depending tapered end of the inner ring section finds the tapered surfaces of the segmental recesses 6 and assists in gathering the segments together. After the lower end of the inner ring section has been thus applied, the operator drives the ring home by tapping upon the outer section 10, the parts finally assuming the position shown in Fig. 2.

In addition to the advantage secured through the gathering operation, the ring

assembly is advantageous in that, as it is driven home it wedges the core segments inwardly or into locking position. Furthermore, this wedging action is secured through the engagement of a small, renewable part with the tapered wall 8. Where the friction is the greatest, the part which is most subjected to wear through such friction is one that can be cheaply and conveniently replaced.

Having thus described my invention, what I claim is:—

1. The combination, with a plurality of core segments each having an arcuate recess therein, one of the lateral surfaces whereof is tapered or inclined and adapted, when the segments are assembled, to form a complete annular recess, of an outer ring section and an inner ring section adapted to be inserted into said recess, one of said ring sections being continuous and the other section being a split ring, one of said ring sections having a surface inclined complementarily to the inclined surface of the recess, and a lost-motion connection between the inner and the outer ring sections.

2. The combination, with a plurality of core segments each having an arcuate recess therein the inner surface whereof is tapered or inclined and adapted, when the segments are assembled, to form a complete annular recess, of an outer ring section and an inner ring section adapted to be inserted into said recess, the outer ring section being continuous and the inner ring section being a split ring, the inner surface whereof is inclined complementarily to the inclined surface of

the recess, and a lost-motion connection between the inner and the outer ring sections.

3. The combination, with a plurality of 40 core segments each having an arcuate recess the inner face whereof is inclined and adapted, when the segments are assembled, to form a complete annular recess, of a ring 45 cooperating with said recess, said ring comprising an outer continuous ring of less width than said recess and an inner split ring having its inner surface inclined complementarily to the inclined surface of the recess, one of said ring sections being provided with a tongue and the other with a groove of greater width than said tongue, whereby a lost-motion connection is provided between said sections.

4. The combination, with a plurality of 55 core segments having an arcuate recess one of the inner faces whereof is inclined and adapted, when the segments are assembled, to form a complete annular recess, of a ring 60 cooperating with said recess, said ring comprising a continuous ring of less width than said recess and a split ring having a surface inclined complementarily to the inclined surface of the recess, one of said ring sections being provided with a tongue and the 65 other with a groove of greater width than said tongue, whereby a lost-motion connection is provided between said sections.

In testimony whereof, I hereunto affix my signature in the presence of two witnesses.

EARLE E. TANNAR.
